UNITED STATES PATENT OFFICE.

IVAN M. SCHNEIBLE, OF GREENWICH, NEW YORK, ASSIGNOR TO ELSIE KINNE
SCHNEIBLE, OF GREENWICH, NEW YORK.

STERILIZER.

1,391,213.

Specification of Letters Patent. Patented Sept. 20, 1921.

Application filed October 29, 1919. Serial No. 334,128.

To all whom it may concern:

Be it known that I, IVAN M. SCHNEIBLE, a citizen of the United States, residing at Greenwich, in the county of Washington and State of New York, have invented certain new and useful Improvements in Sterilizers, of which the following is a specification.

By way of explanation it may be stated that nurses, physicians and others, called upon to employ hypodermic needles, have experienced considerable difficulty in sterilizing instruments of the kind alluded to, the sterilization generally being effected at the bed-side of the patient, or under other conditions which render impractical, the use of sterilizing devices of the sort found in laboratories, physicians' offices and elsewhere.

The foregoing being understood, it may be stated that it is the object of this invention to provide a simple means whereby hypodermic needles may be sterilized, the device being so constituted that, when the occasion for its use has passed, it may be collapsed readily so as to occupy but little space in the pocket or in the bag of a doctor or nurse.

The drawings show merely a typical embodiment of the invention, and it is to be understood that, within the scope of what is claimed, changes in proportions of parts, and other alterations which a mechanic might make, may be resorted to, without departing from the spirit of the invention.

In the accompanying drawings:—

Figure 1 is a side elevation disclosing a device constructed in accordance with the invention, the same being collapsed and in the position which it will assume when not in use;

Fig. 2 is a side elevation showing the structure as it will appear in use;

Fig. 3 is a transverse section, the parts being arranged as they will appear when the device is not in use;

Fig. 4 is a section taken approximately on the line 4—4 of Fig. 3.

In carrying out the invention, there is provided a fuel-holding base 1 which may be variously constructed. The base 1 preferably is a composite structure, embodying a block 2 of fabric, asbestos or other material which will not conduct heat readily. A disk 3 is superposed on the block 2 and includes

a depending flange 4 engaging the periphery of the block 2. The disk 3 is supplied with a depression 5 adapted to receive fuel of any kind. If desired, the fuel may be in the form of a tablet (not shown) shaped to fit more or less closely in the depression 5.

The numeral 6 denotes a top which may have a thickened rim 7, the edge of the rim being threaded as denoted by the numeral 8. The top 6 is connected with the base 1 in any suitable way. If desired, posts 9 may be employed to effect the connection, the posts having reduced ends 10 passing through the disk 3 and the block 2, and through the rim 7 of the top 6, the posts being butt-ended as at 11, to engage the rim 7 of the top and the block 2. The particular means specified for connecting the posts with the other parts of the structure is not insisted upon, but the form shown will be found to be useful. Incidentally, it may be observed that the lower ends of the posts 9 constitute a means for holding the block 2 and the disk 3 of the base together.

The invention comprises an annular casing 12 threaded as shown at 14 to coöperate with the threads 8 of the rim 7 of the top 6. At its lower end, the casing 12 may be supplied with a flange 16, to the upper surface of which a washer 17 is secured. Externally, the casing 12 is provided with ribs 15, to the end that the casing may be rotated readily.

When the device is not in use, the casing 12 is threaded downwardly on the rim 7 of the top 6 until the flange 16 abuts against the disk 3 of the base 1, the upper edge of the casing being substantially flush with the upper surface of the part 7 of the top 6. Obviously, the structure, when arranged as above described, is in compact condition, so that it can be carried in the pocket, in a compartment in a case, or elsewhere.

When the article is to be used, the casing 12 is rotated, and since the casing and the top 6 are threaded together as shown at 100 14—8, the casing will rise until it extends above the top 6, the top then becoming the base or bottom of a sterilizing receptacle, the side wall of which is formed by the casing. In the receptacle above defined, water or a sterilizing liquid of any kind may be placed, the needle being immersed in the contents of the receptacle. The fuel

in the depression 5 is ignited, and the liquid in the receptacle is heated sufficiently to effect a sterilization.

When the casing 12 is elevated as above described, the flange 16 on the casing presses the washer 17 against the under surface of the rim 7 of the top 6, thus insuring a hermetic joint between the casing 12 and the top 6, leakage being avoided. The inner edge of the flange 16 may slide in contact with the posts 9, and the posts, therefore, serve as guides during the raising and lowering of the casing—or, considered conversely, the flange serves to reinforce the posts, so that they will not be bent or distorted. If the threads 14 and 8 are formed with some care, the flange 16 and the washer 17 may not be necessary, but, as a commercial proposition, it may not be expedient to fashion the threads with extreme care and exactness, and, if necessary, the flange and the washer may be used as and for the purposes specified.

Having thus described the invention, what is claimed is:—

1. A device of the class described comprising an imperforate disk-like fuel-holding base; a top; means for connecting the base with the top; and a casing carried by the top and upstanding above the top, to form a sterilizing receptacle closed at its lower end by the top, the casing being movable on the top, toward the base, to effect a collapsing of the device.
2. A device of the class described comprising a fuel-holding base; a top; means for connecting the base with the top; and a casing carried by the top and upstanding

above the top, to form a sterilizing receptacle closed at its lower end by the top, the casing being threaded on the periphery of the top, whereby the casing may be moved toward the base to effect a collapsing of the device.

3. A device of the class described comprising a base and a top and means for connecting the base and the top; a casing threaded on the top to upstand above the top when the casing is raised, and to cooperate with the base when the casing is lowered, the casing having an inwardly projecting annular flange at its lower edge, said flange coöperating with the top, when the casing is raised, to effect a hermetic closure between the casing and the top.

4. A device of the class described comprising a fuel-holding base; a top; means for connecting the base with the top; and a casing threaded on the top for raising and lowering, the casing being provided at its lower end with an inwardly projecting annular flange coacting with the base when the casing is lowered, and coacting with the top to effect a hermetic closure when the casing is raised.

5. A device of the class described comprising a fuel-holding member including a top; and a casing threaded upon said member for raising and lowering, the casing coöperating with the top to form a fuel receptacle when the casing is raised, the upper edge of the casing being substantially flush with the upper surface of the top when the casing is lowered.

In testimony whereof I affix my signature.

IVAN M. SCHNEIBLE.
